UNITED STATES PATENT OFFICE.

ERNEST BRISTOW LE MARE, OF ST. HELENS, ENGLAND, ASSIGNOR TO FILKINGTON BROTHERS LIMITED, OF LIVERPOOL, ENGLAND, A BRITISH COMPANY.

PRODUCTION OF CONTINUOUS STRIPS OF GLASS AND APPARATUS THEREFOR.

Application filed September 16, 1924. Serial No. 728,046.

To all whom it may concern:

Be it known that I, ERNEST BRISTOW LE MARE, a British subject, and resident of "Merle Wood," Kiln Lane, St. Helens, in the county of Lancaster, England, have invented new and useful Improvements in the Production of Continuous Strips of Glass and Apparatus Therefor, of which the following is a specification.

10 This invention relates to processes and apparatus for producing a continuous strip of glass by rolling molten glass issuing from a tank, and has for its object an improved process and improved apparatus whereby the strip produced is flat and free from defects.

15 A continuous strip of glass has heretofore produced by forming a pool of molten metal on a travelling table constituting one member of a rolling apparatus, the pool having the characteristic that it is unconfined except by the other member of the rolling apparatus, that is to say, that it is unconfined laterally and at the back and upwardly (save 20 in or near the pass of the rolling apparatus). The pool having this characteristic is formed by allowing a stream of glass to fall from a spout on to the travelling table, whereby the glass spreads in a backward direction 25 forming a heel behind the stream.

Now the vertical stream and the spreading pool resulting from it, have a large exposed surface which leads to so great cooling that heating means have to be provided to maintain the temperature of the glass, and difficulties have been found in so regulating the action of these heating means as to maintain the correct temperature in all parts of the pool.

30 According to this invention the surface of glass exposed to cooling action, is diminished without losing the unconfined character of the pool in lateral directions, and any special heating means (other than such as may be required in starting the process) are either unnecessary or are so reduced in scope as to present no difficulty in regulation.

In the accompanying drawings:

35 Figure 1 is a vertical section through one

form of the apparatus adapted to carry the invention into effect, showing only the relevant parts thereof;

Figure 2 is a vertical section through another form thereof, and

Figure 3 is a half plan view of the apparatus shown in Figure 2 with the crown of the chute cut away.

Referring to Figure 1, the stream of glass from the tank or other supply of molten glass, flows down the conduit or chute 2 and forms a pool 3 on the travelling table 4, which, with the roller 5, constitutes the rolling apparatus. The table 4 and roller 5 are both wider than the strip 6 formed by them, and the pool 3 is therefore unconfined laterally, the width of the strip being determined by the rate of feed of the glass and the speed of the rolling apparatus.

In Figures 2 and 3 which show an alternative form of apparatus, the same reference numerals apply, except that the table 4 of Figure 1 is replaced by a roller 7.

In both forms of apparatus shown, the outlet of the stream of glass, is brought so close to the lower member of the rolling apparatus, that the conduit or chute serves to confine the pool in a backward direction and prevents its spreading otherwise than forwardly and laterally.

Further, when the strip 6 is considerably wider than the outlet of the chute 2 and in order to prevent any backward flow of the glass after this has spread laterally, the side walls of the chute are extended laterally at the mouth as shown at 8 in Figure 2. The extensions 8 protect the extending portions of the pool from cooling and further prevent any backward flow of the upper portions of the pool which might form folds in the glass and consequent defects in the strip.

The invention is not confined to the particular construction of apparatus shown, and the mouth of the conduit for the stream of glass may, for instance, be above the travelling table or roller and provided with a downwardly extending lip which comes close to the table or roller and serves to confine the pool in a backward direction. Or again, in place of a lip attached to or integral with

the conduit, the pool may be confined by a back wall located between the mouth of the conduit and the table or roller.

Having described my invention, I declare that what I claim and desire to secure by Letters Patent is:—

1. Process of producing a continuous strip of glass consisting in forming a pool of molten metal leading to a pass which forms the strip, the pass dimensions being substantially equal to the thickness of the strip and greater than the width of the strip, characterized by the pool being unconfined in respect to its edges up to and through the pass, but confined in respect to its back end.
2. Process of producing a continuous strip of glass consisting in forming a pool of molten metal leading to a pass which forms the strip, the pass dimensions being substantially equal to the thickness of the strip and greater than the width of the strip, characterized by the pool being unconfined in respect to its edges up to the pass, but confined in respect to its back end.
3. Process of producing a continuous strip of glass consisting in forming a pool of molten metal leading to a pass which forms the strip, the pass dimensions being substantially equal to the thickness of the strip and greater than the width of the strip, characterized by the pool being unconfined through the pass, but confined in respect to its back end.
4. In apparatus for producing a continuous strip of glass, the combination of a rolling apparatus having pass dimensions substantially equal to the thickness of the strip and greater than the width of the strip, and a conduit leading a stream of glass to the rolling apparatus, adapted to form on the lower member of the rolling apparatus a pool of glass which is unconfined in respect to its edges up to the pass and means adapted to confine the back end of the pool.
5. In apparatus for producing a continuous strip of glass, the combination of a rolling apparatus having pass dimensions substantially equal to the thickness of the strip and greater than the width of the strip, and a conduit leading a stream of glass to the rolling apparatus, the conduit being located with its mouth close to the lower member of the rolling apparatus and sufficiently distant from the upper member thereof to permit the formation on the lower member of a pool of glass which is unconfined in respect to its edges to the pass, and is confined with respect to its back end by the conduit.
6. The process of producing a continuous strip of glass, which consists in feeding the molten glass to a forming pass and permitting said glass before entering the pass, to form a laterally spreading pool unconfined

at its sides, while confining the spreading sides of the pool against backward flow.

7. In apparatus for producing a continuous strip of glass, the combination of a rolling apparatus having pass dimensions substantially equal to the thickness of the strip and greater than the width of the strip, a conduit leading a stream of glass to the rolling apparatus adapted to form on the lower member of the rolling apparatus a pool of glass which is unconfined in respect to its edges up to the pass and means adapted to confine the back end of the pool comprising lateral extensions of the side walls of the conduit adapted to prevent backward flow of any portion of the pool of glass.

8. In apparatus for producing a continuous strip of glass, the combination of a rolling apparatus having pass dimensions substantially equal to the thickness of the strip and greater than the width of the strip, a conduit leading a stream of glass to the rolling apparatus, the conduit being located with its mouth close to the lower member of the rolling apparatus and sufficiently distant from the upper member thereof to permit the formation on the lower member of a pool of glass which is unconfined in respect to its edges up to the pass and means adapted to confine the back end of the pool comprising lateral extensions of the side walls of the conduit adapted to prevent backward flow of any portion of the pool of glass.

9. In apparatus for producing a continuous strip of glass, the combination with a travelling table and a roller forming with the table a rolling apparatus having between said table and roller pass dimensions substantially equal to the thickness of the strip and greater than the width of the strip, of a conduit leading a stream of glass to the rolling apparatus, adapted to form on the table a pool of glass which is unconfined in respect of its edges up to the pass and means adapted to confine the back end of the pool.

10. In apparatus for producing a continuous strip of glass, the combination with a travelling table and a roller forming with the table a rolling apparatus having between said table and roller pass dimensions substantially equal to the thickness of the strip and greater than the width of the strip, of a conduit leading a stream of glass to the rolling apparatus, the conduit being located with its mouth close to the travelling table and sufficiently distant from the roller to permit the formation on the table of a pool of glass which is unconfined in respect to its edges up to the pass, and is confined with respect to its back end by the conduit.

11. In apparatus for producing a continuous strip of glass, the combination with a travelling table and a roller forming with

the table a rolling apparatus having between said table and roller pass dimensions substantially equal to the thickness of the strip and greater than the width of the strip, 5 of a conduit leading a stream of glass to the rolling apparatus, adapted to form on the table a pool of glass which is unconfined in respect to its edges up to the pass and means adapted to confine the back end of 10 the pool comprising lateral extensions of the side walls of the conduit adapted to prevent backward flow of any portion of the pool of glass.

12. In apparatus for producing a continuous strip of glass, the combination with a 15 travelling table and a roller forming with the table a rolling apparatus having between

said table and roller pass dimensions substantially equal to the thickness of the strip and greater than the width of the strip, of a 20 conduit leading a stream of glass to the rolling apparatus, the conduit being located with its mouth close to the travelling table and sufficiently distant from the roller to permit the formation on the table of a pool 25 of glass which is unconfined in respect to its edges up to the pass and means adapted to confine the back end of the pool comprising lateral extensions of the side walls of the conduit adapted to prevent backward 30 flow of any portion of the pool of glass.

In testimony whereof I have affixed my signature hereto.

ERNEST BRISTOW LE MARE.
